UNITED STATES PATENT OFFICE.

WILLIAM C. JOHNSON, OF EAU CLAIRE, WISCONSIN.

GUARD.

1,132,853.

Specification of Letters Patent.

Patented Mar. 23, 1915.

Application filed July 24, 1914. Serial No. 852,795.

To all whom it may concern:

Be it known that I, WILLIAM C. JOHNSON, a citizen of the United States, and resident of Eau Claire, in the county of Eau Claire, State of Wisconsin, have invented new and useful Improvements in Guards, of which the following is a description, reference being had to the accompanying drawings, which are a part of this specification.

10 The invention relates to holders.

The invention more particularly designs to provide a detachable eye-glass holder, which is provided with a guard which automatically prevents the glasses from becoming detached from the holder, under certain conditions.

15 The invention further designs to provide an eye-glass holder having a guard which operates automatically to keep the glasses 20 on the holder, should the wearer stoop or bend down.

The invention further designs to provide a new and improved form of holder.

25 The invention consists in the several features hereinafter set forth and more particularly defined by claim at the conclusion hereof.

In the drawings, Figure 1 is an elevation of the device embodying the invention, when 30 it is in upright position. Fig. 2 is a plan view thereof, when it is in inclined position. Fig. 3 is a section taken on the line 3—3 of Fig. 2. Fig. 4 is a section taken on the line 4—4 of Fig. 1.

35 The device comprises a detachable holder 10 which consists of a hook portion 11 and a pin fastener of the safety pin type 12, comprising a pin 13 which is adapted to be sprung into engagement with the notch 14.

40 The upright portion of the fastener, adjacent its upper end, carries bracket 15 with bent up extremities 16, in which are journaled the ends 17 of a guard 18. The guard 18 comprises a transverse member 19, a pair 45 of members or arms 20 depending therefrom and spaced apart, so that the upper portion of the hook 11 is spaced therebetween. The guard 18 carries a stop 21 secured to it at one end, the other end being designed to contact with the upper end of the pin 12, to limit the movement of the guard.

45 The operation of the device is as follows: The holder is attached to the wearer, by securing the pin in the usual way. The eye-glasses may then be secured to the holder,

by securing them to the hook in any well known manner. Now, should the wearer stoop down or bend over, so as to incline the hook to such an extent that the glasses would, due to gravity, or any ordinary circumstances, be released therefrom and fall, the pivoted guard 18 will assume a vertical position due to the action of gravity, and the depending arms of the guard being disposed adjacent the open end of the hook, 60 will close the end and prevent the glasses from being detached therefrom, the movement of the guard being limited by the stop 21.

The invention thus exemplifies a holder 70 which has been described as particularly adapted for holding eye-glasses, but it is obvious that the form of guard which is used may be employed in connection with any hook-like member for securing an 75 article, and which may be tilted.

The invention is not to be restricted to the details of construction herein set forth, but may be varied so as to be within the scope of the appended claims.

80 What I claim is:

1. An eye-glass holder comprising a fastener to secure it to the wearer, means for securing a pair of eye-glasses thereto, and a freely movable guard which is normally 85 inoperative to permit the removal of the glasses from the securing means and which automatically prevents the release of the glasses from the securing means when the wearer stoops over and varies the position 90 of the fastener.

2. An eye-glass holder comprising a detachable fastener to secure it to the wearer, a hook for detachably securing a pair of glasses to the fastener, a gravity actuated 95 guard for said hook which is normally inoperative to permit the removal of the glasses from the hook and which is automatically operative to prevent the release of the glasses from the hook when the wearer 100 stoops over and varies the position of the fastener.

3. An eye-glass holder comprising a detachable fastener to secure it to the wearer, a hook for detachably securing a pair of 105 glasses to the fastener, a freely movable guard pivotally secured to the fastener adjacent said hook and having depending arms adapted to be disposed on either side of the hook and beyond the same, and means for 110

limiting the movement of the guard, said guard being normally inoperative to permit the removal of the glasses from the hook when the wearer is in upright position and 5 being automatically operative to prevent the release of the glasses from the hook when the wearer stoops over.

Copies of this patent may be obtained for five cents each, by addressing the "Commissioner of Patents, Washington, D. C."

In testimony whereof, I affix my signature, in presence of two witnesses.

WILLIAM C. JOHNSON.
